PIPE-LINE RECLAIMER

Seth R. Knapp, Abbeville, La.

Application March 28, 1947, Serial No. 737,969

9 Claims. (Cl. 37—1)

1

This invention relates to improvements in pipe line excavating and reclaiming apparatus designed for raising pipe line buried below the ground surface, with or without the aid of a ditching machine in order that the line may be inspected, repaired, and/or replaced in the ground.

The practice heretofore has been to dig a ditch directly over the buried line to a safe level near the top of the line, pry the pipe upwardly at an angle so as to loosen it from the solid impacted earth above and around the line forming the bottom of the ditch, lift the loosened pipe to the top of and to one side of the ditch, and then backfill the ditch. In thus prying the pipe loose through the solid impacted earth the limit of flexibility of the pipe and of its joints is often exceeded, due to the sharp angle at which the pipe is bent and the amount of force needed to force the pipe through the solid earth, with the result that the pipe is damaged at the joints or couplings and/or bent and flattened at the bottom and must be replaced at considerable expense because it is beyond repair.

An important object of the present invention is to provide apparatus of the type indicated and a method of procedure which substantially reduce or eliminate the above mentioned defects of prior apparatus and procedure, by employment of means which loosens the impacted earth at each side and above the pipe line and then elevates the pipeline through the loosened earth in a gradual rise such that the pipe is not bent to the limit of its normal flexibility and is therefore not subjected to stresses and strains which damage the pipe and its couplings; and the usually separately performed operation of backfilling the ditch being performed in accordance with the present invention concurrently with the removal of the pipeline by a component of the apparatus by means of which the earth forced to either side of the ditch as the pipe is raised to ground level is re-deposited in the ditch as the apparatus is drawn forwardly. The apparatus of the present invention can be used behind a ditching machine in pipe line reconditioning, for elevating the pipe from the ditch to the surface of the ground for reconditioning, following which the pipe can be lowered into the same ditch.

In the cases of certain prior apparatus of the type herein involved, the wedging action of the forward shoe against the pipe pushes the pipe by main force upwardly through solid impacted earth at least for a distance equal to the thick-

ness or the height of the incline of the shoe, thereby subjecting the bottom of the pipe to severe strain, which as indicated hereinabove, often causes overbending of the pipe and flattening of its bottom. Further, the forward shoe of such prior apparatus in being bevelled sufficiently so that it would pass under couplings on the pipe, causes the forward shoe to have a marked tendency to run too deep into the earth beneath the pipe, while the blades or runners exert an upward or inclined pull in the opposite direction, thereby greatly adding to the power required to push the pipe line through solid earth by main force, the power required to overcome the resistance of the shoe to forward movement.

It is accordingly another important object of the present invention to provide for greatly reducing the tractive power requirements of apparatus of this general character, by providing for the loosening of the otherwise solid impacted earth above and at both sides of the pipe for a considerable distance in advance of and before the shoe is passed under the pipe for raising it, in such a way that the earth is loosened above and around a substantial length of the pipe before the pipe is pushed upwardly; and by providing pipe elevating means so designed that its height or incline is such that the pipe is pushed upwardly through the loosened earth at a gradual and safe angle; and by providing construction and arrangement of forward and rear shoes such that deep running and excessive drag are substantially eliminated, the front shoe being self-adjustable to follow the top of the pipe line.

Further important objects of this invention are incorporation of simplicity of construction, avoidance of clogging of the components with earth or debris, provision for cutting through weeds and vegetation in the path of the apparatus, provision for maintaining the components of the apparatus in operative relation to the pipe line even when the tractor is not moved accurately and evenly over the pipeline and for avoiding damage to the pipe line and to the apparatus when pulled at an angle to the lay of the pipeline.

Other important objects and advantageous features of this invention will be apparent from the following detailed description and accompanying drawings, wherein, merely for purposes of illustration, a presently preferred embodiment is set forth.

In the drawings:

Figure 1 is a general right hand side elevation

of said embodiment, omitting the drag shown in Figure 7.

Figure 2 is a top plan view of Figure 1.

Figure 3 is a transverse vertical section taken on the line 3—3 of Figure 1.

Figure 4 is a plan view of the forward excavator shoe.

Figures 5 and 6 are transverse vertical sections taken on the lines 5—5 and 6—6, respectively, of Figure 1.

Figure 7 is a side elevation of the drag.

Figure 8 is a top plan view thereof, and

Figure 9 is a front end elevation thereof.

Referring in detail to the drawings, the illustrated apparatus according to this invention combines in a single string the excavator 10, the elevator 11, and the drag 12 for performing in concurrent succession the operations of excavating or unearthing the pipe line 13 from the floor of the ditch 14 below the ground level 15, elevating the section of pipe over and around which the excavator loosened the earth, and backfilling or returning into the ditch the earth displaced by the excavator and by the elevating of the pipe section. The excavator 10 and elevator 11 are necessarily to be drawn along together by the same tractor, while the drag 12, which can also be utilized as a cradle for handling pipe, need not be connected in the same string with the excavator, but may be drawn either by a separate cable 16 leading from the same tractor or by a separate tractor, as circumstances may indicate.

The excavator 10 comprises two similar triangular plates 17 parallelly spaced at a distance to clear opposite sides of the pipe line 13. At upper and lower points on the rearwardly declining edges of the side plates 17 they are spaced and connected by webs 18 and 19, respectively, and another similar web 20 is connected to and between the upper ends of the forwardly declining edges of said side plates, these edges being bevelled as indicated at 21 for cutting effect.

The major portion of the lower edges 22 of the side plates 17 are normally substantially parallel with and slightly above the top of the pipe line 13, so that debris incidental to the excavating can escape and not lodge within the excavator and pack around the pipe. This elevation of the lower edge portions 22 is sufficiently high and long to permit the excavator to ride the pipe line 13 even if the excavator be drawn forwardly somewhat out of line with the pipe line 13. An extreme rear portion 23 of the side plate depends below the lower edge 22 to a depth about equal to the diameter of the pipe line, and connected to and between the lower ends of the portions 23 is a fixed horizontal rear shoe 24, having a forward edge which has a notch 25 with a sufficiently wide aperture to enable the forward edge of the shoe to encounter pipe couplings without injury thereto or to the shoe. The notched edge of the shoe 24 is bevelled downwardly enough to present to the earth a non-resistant forward edge, and not enough to cause the shoe to ride deep into the earth.

Depending portions 26 on the forward extremity of the lower edge of the side plates 17 extend downwardly only about half the diameter of the pipe line, and have their horizontal lower edges bevelled to act as cutting runners, as indicated at 27. On about a level with the position of the top of the pipe line 13 or about half the height of the pipe 13 above the rear shoe 24, the excavator has the forward shoe 28.

The forward shoe 28, shown in detail in Figure 4, comprises a flat heavy plate of generally rectangular form having a notch 29 cut in its forward edge of wide enough aperture to enable the shoe to clear around pipe couplings, and bevelled downwardly as indicated at 30. Headed pivots 31 project laterally from the opposite side edges of the shoe 28 at a distance about one-third back from the forward extremity of the shoe, and turn in holes formed in the side plates 17, the arrangement of the pivots being such that the major portion of the shoe behind the pivots will overbalance the shoe rearwardly and raise the front end, thereby overcoming any tendency which might otherwise exist for the shoe to ride deep in the earth or jam against or be upset by engagement with a pipe coupling 32 or other obstruction. The pivotal and overbalanced mounting of the forward shoe 28 is such that when the excavator 10 is engaged with a pipeline in normal operation, the forward shoe 28 will more or less constantly ride upon the top of the pipe and thereby be held in best position not only for offering minimum resistance against forward movement but for undercutting the earth immediately above the pipe line, just as the rear shoe 24 which immediately underrides the pipe line undercuts the earth thereunder.

The side plates 17 have arcuate slots 33 in the upper forward part thereof whose center of curvature is located in the rear shoe 24, so that pull exerted forwardly in the region of the slots will tend to swing the excavator forwardly and downwardly with the rear shoe as a center, thereby keeping the excavator at that proper angle in which the forward shoe 28 is engaged with the top of the pipe line and the rear shoe 24 is engaged with the bottom of the pipe line 13.

Pairs of draft bars or blades 34 are connected to and on opposite sides of each side plate 17 of the excavator 10 by means of bolts 35 working in the arcuate slots 33, whose forward edges are provided with vertically spaced notches 36, with which the draft bar bolts 35 are to be selectively engaged in accordance with the depth or thickness of the earthen ditch floor. Instead of being straight the draft bars or blades 34 comprise rear sharply inclined portions 37 and forward less sharply declining portions 38 to the forward ends of which are pivoted the eyes of a clevis 39, to which the tractor chain or cable 40 is connected. A weed cutting wheel 41 having a cutting edge 42 is rotatably mounted just behind the clevis on an axle 43 mounted on and between the draft bars 34. Shaped and arranged in this way the draft bars or blades exhibit less tendency to catch debris and roots. On the outside of the side plates 17, about on a level with the lower end of the arcuate slots 33 are headed studs 44 with which are connected the forward ends of draft cable or rods 45 for pulling the elevator 11 in line behind the excavator 10.

The elevator draft cables or rods 45 are of such lengths that a relatively great length of the pipe line 13 behind the excavator shall have been loosened in the earth by the excavator, before the elevator 11 begins to elevate the pipe out of the earth, thereby making provision against undesirable upward strain upon and sharp bending of the pipe in elevating the same.

The elevator 11 comprises an open top semi-circular cross section trough 46 of sufficient length to provide substantial support to the pipe line and a gradual ramp for elevating the pipe out of the loosened earth behind the excavator

10 at a safe angle. Extrusions 47 rise from the sides of the forward end of the trough and have outside headed studs 48 at a level slightly above the top of the pipe line 13, for connecting the rear ends of the draft cables or rods 45 to the elevator. Supporting the trough 46 at the desired rearward inclination are laterally spaced tubular runners 49, which are gradually reduced toward their forward ends to merge with the underside of the forward end of the trough, with their rearward portions spaced from and connected to the bottom of the trough by webs 50, as indicated in Figures 1 and 6. The forward and slight upward pull exerted by the draft cables or rods 45, due to the location of the excavator draft studs 44 above the elevator draft studs 48, and the position of the studs 48 slightly above the level of the pipe line 13, produces stabilization of the elevator runners 49 in a substantially parallel position relative to the unelevated portion of the pipe line as the elevator is moved forwardly. Between the ends of the trough 46 the sides are cut away as indicated at 51, to discharge debris otherwise tending to accumulate in the trough and interfere with the smooth elevation of the pipe, and to permit the trough to retain engagement with the pipeline when canted with respect thereto, as when a boulder or other unusual resistance is encountered which throws the elevator sidewise out of line with the pipe.

The drag 12, shown in Figures 7, 8 and 9, comprises a frame consisting of a longitudinal channel 52 for receiving and loosely cradling the pipe line 13, and several cross members in the form of flat transversely elongated plates 53, 54 and 55, equally spaced from each other from the front to the rear end of the channel 52 and secured to project equally on opposite sides of the bottom thereof. The cross members diminish in width from front to rear, as indicated in Figure 8. The front cross member 53 has two draft studs 56 to which the rear ends of the draft cables 16 are connected.

Hinged to their upper edges at 57, 58 and 59 to the outer conformably angulated ends of the cross members 53, 54 and 55, respectively are the flat rectangular blades 60, which are thereby mounted to depend from the drag frame in rearwardly converging relationship, as shown in Figure 8, with their front and rear ends extending slightly forwardly of the front cross member 53 and rearwardly of the rear cross member 55, respectively. The spread of the blades 60 at their forward ends is provided to gather therebetween the earth thrown along the sides of the ditch 14 by the excavator 10 and the rising of the pipeline through the loosened earth, while the approach of the rear ends of the blades is gauged to confine the gathered earth to the width of and return it into the furrow therein created by the displacement of the pipe line. The hinging of the blades 60 is provided so that their lateral reach can be adjusted from the minimum defined by the perpendicular positions shown in full lines, in Figures 8 and 9 to the maximum out swung positions indicated in dotted lines in Figure 9.

Adjusting means for holding the blades 60 in their minimum and maximum, and in intermediate such position, is provided in the form of front and rear angle iron brackets 61 and 62, respectively, secured to the outer sides of the blades and rising thereabove and above the trough 52 and pivotally connected at their up-

per ends to links 63 which are connected to front and rear lugs 64 and 65, respectively, projecting from the sides of the trough 52 and secured to the front and rear cross members 53 and 55, respectively. Bolts 66 and 67 on the lugs 64 and 65, respectively, are arranged to be engaged in selected ones of longitudinally spaced bolt holes 68 in the links 63, whereby the blades 60 can be adjusted into and held in the desired adjusted positions.

In running the string for reclaiming and reconditioning the pipe line 13, the draft cables 16 of the drag 12 may be secured to the same tractor (not shown) as is used to draw the excavator 10 and the elevator 11, or a separate tractor may be used to draw the drag 12, or the cables 16 of the drag may be connected to the elevator 11, whereby the excavated and thrown up earth may be put back in the ditch as the pipe is reconditioning and returned into place in the ditch. Further the drag 12 may be disconnected from the string and used separately or concurrently as a cradle for handling exposed portions of the pipe line, with the aid of a crane or the like.

What I claim is:

1. Apparatus for reclaiming buried pipeline, comprising an excavator comprising a pair of vertical side plates secured in laterally spaced relation at a distance slightly greater than the diameter of the pipeline to be reclaimed and its couplings, said side plates being of substantial length so as to extend for a substantial distance along the pipeline and of substantial height, the forward edges of said side plates declining forwardly and having cutting bevels thereon, a rear earth cutting shoe positioned between said side plates adjacent to the rear end of said excavator for under-riding the pipeline, a front earth cutting shoe positioned between said side plates adjacent to the forward end of said excavator on a level above said rear shoe for overriding the pipe line, pivoting means carried by said side plates and front shoe forwardly of the center of gravity of said front shoe to permit said front shoe to tilt upwardly in contact with the upper side of the pipeline, and draft means connected to the upper part of said excavator adjacent to the forward declining edges of said side plates, whereby forward pull upon said draft means operates to move said excavator forwardly through the earth with said rear shoe following the underside of the pipeline and said front shoe following the upper side of said pipeline.

2. Apparatus for reclaiming buried pipeline, comprising an excavator comprising a pair of vertical side plates secured in laterally spaced relation at a distance slightly greater than the diameter of the pipeline to be reclaimed and its couplings, said side plates being of substantial length and of relatively great height and having declining forward edges, cutting bevels on the forward edges of said side plates, a rear earth cutting shoe positioned between said side plates adjacent to the rear end of said excavator for under-riding the pipeline, a front earth cutting shoe positioned between said side plates adjacent to the forward end of said excavator on a level above said rear shoe for overriding the pipeline, and draft means connected to an upper part of said side plates adjacent to the declining forward edges thereof, whereby forward pull upon said draft means operates to move said excavator forwardly through the earth with said rear shoe following the underside of the pipeline.

and said front shoe following the upper side of said pipeline, said rear and front shoes each consisting of a generally horizontal flat plate having a downwardly bevelled forward edge of relatively low vertical profile whereby said shoes can cut forwardly through the earth without marked tendency to ride deep into the earth.

3. Apparatus for reclaiming buried pipeline, comprising an excavator comprising a pair of vertical side plates secured in laterally spaced relation at a distance slightly greater than the diameter of the pipeline to be reclaimed and its couplings, said side plates being of substantial length so as to extend for a substantial distance along the pipeline, cutting bevels on the forward edge of said side plates, a rear earth cutting shoe positioned between said side plates adjacent to the rear end of said excavator for under-riding the pipeline, a front earth cutting shoe positioned between said side plates adjacent to the forward end of said excavator on a level above said rear shoe for overriding the pipeline, and draft means connected to an upper forward part of said excavator, whereby forward pull upon said draft means operates to move said excavator forwardly through the earth with said rear shoe following the underside of the pipeline and said front shoe following the upper side of said pipeline, said front shoe being pivotally flexibly mounted on said excavator whereby said front shoe can maintain floating engagement with the upper side of the pipeline during rises and falls of said excavator during its forward movement.

4. Apparatus for reclaiming buried pipeline, comprising an excavator comprising a pair of vertical side plates secured in laterally spaced relation at a distance slightly greater than the diameter of the pipeline to be reclaimed and its couplings, said side plates being of substantial length so as to extend for a substantial distance along the pipeline, cutting bevels on the forward edges of said side plates, a rear earth cutting shoe positioned between said side plates adjacent to the rear end of said excavator for under-riding the pipeline, a front earth cutting shoe positioned between said side plates adjacent to the forward end of said excavator on a level above said rear shoe for overriding the pipeline, and draft means connected to an upper forward part of said excavator, whereby forward pull upon said draft means operates to move said excavator forwardly through the earth with said rear shoe following the underside of the pipeline and said front shoe following the upper side of said pipeline, said rear and front shoes each comprising generally horizontal flat plates having downwardly bevelled forward edges of relatively low vertical profile whereby said shoes can cut forwardly through the earth without marked tendency to ride deep in the earth, said front shoe being pivotally mounted on a horizontal axis extending transversely of said excavator with the said axis located at a forward part of said front shoe whereby said front shoe is overbalanced rearwardly so that its rear part tends to be maintained in floating engagement with the upper side of the pipeline by gravity and the downward pressure of the earth between the side plates during forward movement of said excavator.

5. Apparatus for reclaiming pipeline buried beneath the ground, comprising an excavator arranged to be drawn forwardly along the pipeline so as to loosen the earth along and above the pipeline, an elevator comprising a substantially semi-cylindrical trough in which the pipeline can

slide lengthwise, a pair of laterally spaced runners, means connecting said runners to opposite sides of the underside of said trough whereby said trough has a gradual rearward inclination with respect to said runners, at an insufficiently sharp angle to subject the pipeline to excessive bending and upward pressure, vertical projections at the forward ends of the sides of said trough, draft connections on said projections at levels above the top of the trough whereby forward pulls of draft means on said draft connections tends to tilt said elevator forwardly so as to maintain said trough in engagement with the underside of the pipeline for elevating the same.

6. Apparatus for reclaiming pipeline buried beneath the ground, comprising an excavator arranged to be drawn forwardly along the pipeline so as to loosen the earth along and above the pipeline, an elevator comprising a substantially semi-cylindrical trough in which the pipeline can slide lengthwise, a pair of laterally spaced runners, means connecting said runners to opposite sides of the underside of said trough whereby said trough has a gradual rearward inclination with respect to said runners, at an insufficiently sharp angle to subject the pipeline to excessive bending and upward pressure, vertical projections at the forward ends of the sides of said trough, draft connections on said projections at levels above the top of the trough whereby forward pulls of draft means on said draft connections tends to tilt said elevator forwardly so as to maintain said trough in engagement with the underside of the pipeline for elevating the same, the sides of said trough between forward and rearward portions thereof being cut away for a sufficient distance to permit said trough to retain engagement with the pipeline even when said elevator moves forwardly at a lateral angle to the axis of the pipeline.

7. Apparatus for reclaiming buried pipeline, comprising an excavator comprising a pair of vertical side plates secured in laterally spaced relation at a distance slightly greater than the diameter of the pipeline to be reclaimed and its couplings, said side plates being of relatively great height and having declining forward edges, cutting bevels on the forward edges of said side plates, a rear earth cutting shoe positioned between said side plates adjacent to their rear ends for under-riding the pipeline, a front earth cutting shoe positioned between said side plates adjacent to their forward ends on a level above said rear shoe, said front shoe having a downwardly bevelled forward cutting edge, and draft means connected to upper forward portions of said side plates, whereby forward pull upon said draft means operates to move said excavator forwardly through the earth so as to cut and loosen the earth above and at the sides of the pipeline and loosen the same while causing said rear shoe to follow the underside of the pipe line and said front shoe to follow the upper side of said pipeline.

8. Apparatus for reclaiming buried pipeline, comprising an excavator comprising a pair of vertical side plates secured in laterally spaced relation at a distance slightly greater than the diameter of the pipeline to be reclaimed and its couplings, said side plates being of relatively great height and having declining forward edges, cutting bevels on the forward edges of said side plates, a rear earth cutting shoe positioned between said side plates adjacent to the rear end thereof for under-riding the pipeline, a front

earth cutting shoe positioned between said side plates adjacent to the forward end of said excavator on a level above said rear shoe for overriding the pipeline, and draft means connected to an upper forward part of said excavator, whereby forward pull upon said draft means operates to move said excavator forwardly through the earth with said rear shoe following the underside of the pipeline and said front shoe following the upper side of said pipeline, the lower edges of said side plates between said front and rear shoes being cut away to a bevel above said front and rear shoes whereby the excavator can maintain engagement with the pipeline even when said excavator is moved forwardly at a lateral angle to the axis of the pipeline.

9. Apparatus for reclaiming buried pipeline, comprising an excavator comprising a pair of vertical side plates secured in laterally spaced relation at a distance slightly greater than the diameter of the pipeline to be reclaimed and its couplings, said side plates being of substantial length so as to extend for a substantial distance along the pipeline, cutting bevels on the forward edges of said side plates, a rear earth cutting shoe positioned between said side plates adjacent to the rear end of said excavator for under-riding the pipeline, a front earth cutting shoe positioned between said side plates adjacent to the forward end of said excavator on a level above said rear shoe for overriding the pipeline, and draft means comprising earth cutting blades connected to an

upper forward part of said excavator, whereby forward pull upon said draft means operates to move said excavator forwardly through the earth with said rear shoe following the underside of the pipeline and said front shoe following the upper side of said pipeline, said earth cutting blades comprising pairs of forwardly projecting bars having a clevis connected to and between their forward ends, said bars being upwardly angulated between their ends and formed on their forwardly facing edges with earth cutting bevels, the rear ends of said bars having pivot means selectively engageable with notches formed along the length of arcuate slots formed in said side plates with their centers of curvature located in said rear shoe, whereby said pivot means can be engaged with selected notches in accordance with the depth of the earth overlying the pipeline so as to insure running of the excavator at a proper depth along the pipeline.
